UNITED STATES PATENT OFFICE.

HUGH E. SHEDD, OF RED WING, MINNESOTA.

CALENDAR.

SPECIFICATION forming part of Letters Patent No. 795,009, dated July 18, 1905.

Application filed March 28, 1905. Serial No. 252,507.

ISSUED

To all whom it may concern:

Be it known that I, HUGH E. SHEDD, a citizen of the United States, residing at Red Wing, in the county of Goodhue and State of Minnesota, have invented certain new and useful Improvements in Calendars; and I do hereby declare that the following is a full, clear, and exact description of the same, reference being had to the annexed drawings, making a part of this specification, and to the letters of reference marked thereon.

The present invention has reference to that class of calendars either in tablet form or in which the leaflets are loose and held together at their upper ends by suitable means which will admit of each leaflet being torn off or thrown up out of the way as required.

The object of the invention is to provide a calendar having the desired number of leaflets to correspond with the days of the month or months of the year, each leaflet having thereon the day or days of the month which have passed and also the day following, and as each day passes the leaflet is removed to expose the leaflet under it, which latter has thereon the days that have passed, with the next day following, the numerals indicating the days that have passed and the day following being of different color or design, so as to distinguish them from each other.

The invention consists in a calendar substantially as shown in the drawings and hereinafter described.

Figure 1 of the drawings is a front elevation of a calendar embodying my invention; Fig. 2, a similar view showing several of the leaflets removed up to the twenty-first day of the month; Fig. 3, a detail view in perspective of one of the leaflets; Fig. 4, a detail view in perspective of the lower end of a yearly calendar, the last one of each series of leaflets of a month being provided with a tab with a distinguishing-mark thereon to indicate the month of the year.

In the accompanying drawings, A represents the back of the calendar, which may be of any suitable material of sufficient stiffness or rigidity, and the leaflets B are held thereto by suitable fastenings *a*, as shown in Figs. 1 and 2 of the drawings. The back and means of

fastening or holding the leaflets together may be changed or modified as found most preferable without in any manner departing from the essential feature of the invention, this being left to the discretion of the manufacturer. 55 The leaflets B have the names of the days of the week thereon and also the month and the numeral representing the year, and in the present instance I have shown the calendar for the month of February, 1905, the twenty-eight days being represented by numerals. Each leaflet, with the exception of the first, has a numeral or numerals indicating the days that have passed and a numeral indicating the current day, the days that have passed being 60 represented by the open-line numerals *b* and the current day being represented by solid-black numerals *c*, as shown in Fig. 3 of the drawings. In order to distinguish the days passed and the current day on each one of the 65 leaflets, it is necessary to have the numerals of different designs or styles or of different colors, as found most preferable, and to represent one of many styles of numerals that may be used. The numerals are represented by 70 open-line numerals and solid-black numerals or any distinguishing form or shape or color of numerals may be substituted as found best adapted to the purpose. The leaflets B are 75 cut so as to display only the numerals or dates 80 of the days passed and in addition thereto the numeral of the current day only.

In Fig. 1 of the drawings is shown a complete calendar for the month of February, having twenty-eight days, and consequently 85 twenty-eight leaflets corresponding to the number of days in the month, and after the first day of the month has passed the leaflet bearing the numeral "1" is removed to expose the leaflet under it, which leaflet is shown 90 in Fig. 3 of the drawings. It will now be seen that the first day of February having already passed that day will be represented on the leaflet as of a different form, style, or color from that of the second day of the month, 95 which has not as yet passed, and so on throughout the series of leaflets. When the twentieth day of February has passed, the leaflet on which the last numeral is "20" is removed, 100 thus exposing to view the leaflet immediately

under it, which leaflet is shown in Fig. 2 of the drawings, and the days that have passed from the first to the twentieth, inclusive, are shown on the leaflet in a different color or design from that of the twenty-first of the month, thus designating the present day from the days that have gone before. The numerals indicating the Sundays of the month may be of the same color or design as the numerals representing the days that have passed, any color or design being used as found most preferable.

In Fig. 4 of the drawings is shown a portion of a calendar C for the entire year and does not differ from the leaflets hereinbefore described with the exception that the last one of each series of leaflets of a month is provided with a tab d, having a distinguishing-mark thereon to designate the month, preferably an abbreviation of the month, as shown, thereby enabling the several leaflets comprising a month to be lifted up out of the way when desired.

Having now fully described my invention,

what I claim as new, and desire to secure by Letters Patent, is—

1. A calendar comprising a plurality of leaflets, each leaflet having thereon suitable numerals indicating the days that have passed and a numeral indicating the current day only, each class of numerals being of different color or design to distinguish them from each other, substantially as and for the purpose set forth.

2. A calendar comprising a plurality of leaflets, each leaflet having thereon suitable numerals indicating the days that have passed and a numeral indicating the current day only, the last one of the series of leaflets of each month having a tab with distinguishing-mark to designate the month, substantially as and for the purpose specified.

In testimony whereof I affix my signature in presence of two witnesses.

HUGH E. SHEDD.
